PUMP SEALING MEANS

William F. Macdonald, Bridgeport, Conn., assignor, by mesne assignments, to Bridgeport Thermostat Company, Inc., Bridgeport, Conn., a corporation of Delaware

Application June 4, 1935, Serial No. 24,894

4 Claims. (Cl. 103—111)

This invention relates to pumps provided with sealing means for preventing the escape of liquid from the pumping chamber around the driving shaft.

5 In the pumps now in use there is always difficulty with preventing water leakage around the driving shaft. Especially is this true with water pumps used for circulating water in the cooling system of automobiles. It is necessary to have 10 the pump shaft sealed or there will be a loss of cooling medium. Also in winter if the shaft is not properly sealed, there is a loss of anti-freeze solution. In the present devices packing glands are used which become worn and which must be 15 replaced or tightened to prevent leakage.

An object of this invention is to overcome the defects and difficulties present in the pumps now in use and to provide a sealing means for liquid pump shafts which will prevent the escape of 20 liquid from the pump casing and which after it is once installed does not need any adjustment or repair for an indefinite period.

In the drawing:

Figure 1 represents a vertical, transverse cross 25 section of a pump and pump housing;

Figure 2 represents a view in elevation of the pumping and sealing unit; and

Figure 3 represents an elevation of the impeller.

Referring now to the drawing, the reference 30 character 10 designates a pump housing having a closure plate 12 secured to the pump housing so as to form a water-tight joint. The plate may be secured to the housing by the bolts 13 or in any suitable manner. A gasket or packing 14 is provided between the plate 12 and the housing 10. This housing may form part of an engine for an automobile or may be made separate and attached to the engine. Rotatably mounted in and extending into the pump housing 10 is a shaft 16 35 which may be rotated in the usual manner by a pulley 17 or which may be rotated by the engine by means of a belt, gearing or in any suitable manner. The bearing 18 is provided for the shaft 16. It is to be noted that the shaft 16 does 40 not extend through the closure plate 12.

Secured to the end 20 of the shaft 16 by means of the pin 22 is a pump impeller 24. As shown in the drawing, the impeller is formed from a single piece of metal. The impeller 24 is provided with the closed socket 26 into which the end 20 of the shaft 16 fits. Extending from and formed integrally with the socket 26 is the annular portion 28 which is bent at right angles to the socket 26. Beyond the annular portion 28 55 the pump impeller is bent back to form the

cylindrical portion 30 which is concentric with the socket 26. Adjacent the annular portion 28, the cylindrical portion 30 has a shoulder 32 and a reduced portion 34 to receive a portion of the sealing member later to be described. The portion 30 is bent at right angles to form arms 36 which are substantially in the same plane as the bottom of the socket 26. At the outer ends of the arms 36 are the vanes 38 bent at right angles to the arms 36, the vanes 38 being substantially 10 in line with the axis of the socket 26 of the impeller 24. The arms 36 and the vanes 38 are provided with ribs 40 which form reinforcing members for the arms and the vanes. As before stated, the pump impeller is secured to the shaft 16 by the pin 22, and as the shaft 16 rotates, the impeller 24 will be rotated to cause pumping of the liquid contained within the pump housing 10.

In order to prevent the liquid from leaving the pump housing 10 and escaping therefrom around 20 shaft 16 I have provided the following construction. The pump housing 10 is provided with a fixed collar or annular projection 44 adjacent the bearing 18. Between the collar or projection 44 and the annular portion 28 of the pumping impeller, is positioned a resilient extensible and contractible member 46 provided with an annular bearing member 48 which surrounds the shaft 16 and bears against the collar or projection 44. As the extensible and contractible member 46 I 25 prefer to use a flexible metallic bellows which functions as a bellows seal for the shaft 16. This resilient and flexible member 46 at its one end is provided with a flange portion 50 which is spun over the flange 52 on the annular bearing member at 54 to secure the bellows member 46 to the bearing member 48. The other end of resilient member 46 has a flange or sleeve portion 55 which fits the reduced portion 34 of the cylindrical portion 30 of the impeller. The flange 40 or sleeve portion 55 is soldered or otherwise securely attached and sealed to the impeller in this way.

The bearing member 48 may be made of metallic or of non-metallic bearing material. If the bearing material is metal, the resilient member 46 is soldered or otherwise secured thereto and the flange 50 then spun over as at 54. If the bearing member 48 is of non-metallic material, 50 the bellows member or resilient member 46 is cemented thereto and the flange 50 then spun over as at 54. For a non-metallic bearing material I may use moulded material similar to Bakelite. When such material is used, I employ 55

cement to attach the flange 50 of the flexible sealing member 46 to the bearing member 48.

Positioned within the resilient and flexible sealing member 46 is a spring 56, one end of which bears against the annular portion 28 of the pumping impeller and the other end of which bears against the annular bearing member 48. This spring 56 functions to expand the flexible sealing member 46 and to keep the bearing member 48 in sealing engagement with the collar 44 of the pump housing and to prevent the leakage of any liquid from the pumping chamber past the shaft 16. The spring is of sufficient strength to keep the parts sealed. While I have shown the spring 56 as a coil spring, I may substitute other forms of springs therefor.

From an inspection of Fig. 2 it will be apparent that the pump and sealing member are a unit which may be sold as such.

From the above description it is believed that the operation of the device will be obvious but the operation will be briefly given. The shaft 16 is rotated by the pulley 17, or gearing or the like. Because the shaft 16 is connected to the pumping impeller 24 by the pin 22, rotation of the shaft 16 will cause rotation of the pumping impeller. The resilient and flexible sealing member 46 is fixedly attached to the pumping impeller at 34 and 55 and also to the annular bearing member 48 at 50 and 56 so that rotation of the impeller 24 will also cause rotation of the resilient and flexible sealing member 46, the bearing member 48 and the spring 56. Rotation of the impeller will cause pumping of the liquid in the pumping chamber but due to the sealing arrangement, no liquid will escape past the shaft 16.

In view of the above description it will be seen that I have set forth an extremely simple and effective pump sealing structure which will last indefinitely.

What I claim is:

1. An impeller made of sheet metal and shaped to include a closed ended socket having an open mouth adapted to receive the end of a shaft, an annular flange portion at said mouth extending at right angles to the circumferential wall of said socket, a cylindrical portion concentric with said socket and connected with the annular flange portion, and a radially extending portion carrying impeller vanes and connected to said cylindrical portion.

2. An impeller made of sheet metal and provided with a closed shaft receiving socket and having an annular bent-back portion concentric with said socket and connected with the same, said impeller being also provided with a radially extending portion carrying impeller vanes and connected with said annular portion, a resilient

and flexible corrugated sealing member provided with a flange at one end fixedly secured to said annular portion of said impeller, an annular bearing member secured to the other end of said resilient and corrugated sealing member, and a spring within said resilient and flexible corrugated member bearing against said impeller and said annular bearing member, said impeller, sealing member, bearing member and spring constituting a unitary replacement unit for use in a 10 pump adapted to be unitarily mounted upon or removed from a pump shaft.

3. An impeller made of sheet metal and shaped to include a closed ended socket having an open mouth adapted to receive the end of a shaft, an 15 annular flange portion at said mouth extending at right angles to the circumferential wall of said socket and connected therewith, a cylindrical portion concentric with said socket and connected with the annular flange, a radially extending portion carrying impeller vanes and connected to said cylindrical portion, a flexible metallic corrugated sealing member having an annular flange at one end thereof soldered to said cylindrical portion, an annular bearing member mounted at 25 the opposite end of said sealing member, and a spring mounted in said sealing member whose opposite ends bear respectively against said annular flange portion of said impeller and said annular bearing member, said impeller, sealing 30 member, bearing member and spring constituting a unitary replacement unit for pumps adapted to be removably mounted on a pump shaft.

4. An impeller made of sheet metal and shaped to provide a closed socket adapted to receive an 35 end of a shaft, an annular flange portion extending at right angles to the circumferential wall of said socket and connected therewith, a second bent-back portion extending at right angles to said first-named annular flange portion concentric with said circumferential wall and connected to the annular flange portion, a radially extending portion carrying impeller vanes and connected with said bent-back portion, a resilient and flexible corrugated sealing member having an annular 45 flange at one end fixedly secured to said bent-back portion of said impeller, an annular bearing member secured to the other end of said resilient and flexible corrugated sealing member, and a spring within said flexible corrugated sealing member whose opposite ends bear respectively against the inner face of said annular bearing member and said annular flange portion of said impeller, said impeller, sealing member, bearing member and spring constituting a unitary replacement unit for pumps adapted to be removably mounted on a pump shaft.

WILLIAM F. MACDONALD.
